TURNBUCKLE

James H. Booth, Venice Township, Shiawassee County, Ohio, assignor to Thompson Products, Inc., Cleveland, Ohio, a corporation of Ohio

Application July 20, 1950, Serial No. 174,871

1 Claim. (Cl. 287—60)

This invention relates to an improved type of turnbuckle for adjustably attaching two connecting members.

More specifically, the invention relates to an improved turnbuckle of generally tubular construction having an expanded central portion giving added strength to the turnbuckle barrel and which has turned out lugs for retaining clamps on each end in proper longitudinal position on the barrel. The invention also includes the method of making the turnbuckle barrel.

According to this invention a generally tubular turnbuckle barrel, which may be formed by rolling a blank of sheet metal into the desired tubular shape, is formed of a central portion of slightly larger diameter than with a central portion of slightly larger diameter than with the end portions. The end portions are internally threaded with right-hand threads within one end portion and left-hand threads within the other. Slots are formed axially inwardly through the wall of the barrel from each end thereof and extend almost to the central portion. Clamping rings are inserted over the ends of the barrel and have bolts extending across the slots in the barrel. When connecting members have been threadededly inserted into the internally threaded ends, the clamps can be tightened on the barrel ends serving to squeeze the ends of the barrel tightly about the attached ends of the connecting members. Tabs are pressed out of the metal of the barrel at either side of each clamping ring at points substantially diametrically opposite the slots, and these tabs serve to retain the clamps on the ends of the barrel even when the clamps are loosened to permit rotation of the turnbuckle barrel about the ends of the connecting members.

The turnbuckle of the present invention, having an increased diameter central portion, has several distinct advantages over the conventional turnbuckle of this type. The portion which is unsupported is the portion of the barrel most likely to fail under a heavy load. By increasing the diameter of the unsupported central portion the section modulus is thereby increased and thus the tube is strengthened. In addition, due to the increased inside diameter of this central portion, the internal threads cut at the ends do not extend into the central portion, leaving it free from weakening notches which make for high stress concentrations and consequent early failure under load. Furthermore, the turnbuckle of the present invention need have threaded sections only as long as the minimum required threaded engagement since the larger central portion provides an unthreaded chamber allowing for adjustment between the ends of the connecting members. In the conventional design, in order to provide the necessary adjustment length, the thread must be substantially longer than the minimum required engagement.

It is, then, an object of this invention to provide a turnbuckle assembly which has an enlarged diameter central portion with a consequent increased section modulus and a smooth unthreaded inner surface in the central portion.

A further object of the invention is to provide a turnbuckle barrel with an enlarged central portion with internally threaded end portions of minimum required threaded lengths.

A further object of the invention is to provide a turnbuckle assembly having clamping rings at either end and having tabs pressed outwardly from the metal of the turnbuckle barrel on either side of each of the clamping

rings for retaining the clamping rings on the turnbuckle barrel.

Another object of the invention is to provide a turnbuckle barrel having an enlarged central portion which may be easily and inexpensively formed by rolling a piece of flat metal sheet into the desired shape.

Still another object of the present invention is to provide a novel turnbuckle barrel of increased strength without necessitating a substantial change in existing methods of manufacture and without using a heavier gauge of metal sheet.

Other and further objects of the invention will be apparent to those skilled in the art from the following detailed description of the annexed sheet of drawings which, by way of preferred example only, illustrate one embodiment of the present invention.

On the drawings:

Figure 1 is a perspective view of a substantially flat metal blank as used in forming the turnbuckle barrel of the present invention with a formed barrel shown in dashed outline superimposed on the blank;

Figure 2 is a plan view of a turnbuckle barrel according to the present invention;

Figure 3 is a side elevational sectional view of the barrel shown in Figure 2;

Figure 4 is a side elevational view of a turnbuckle according to the present invention with clamping rings thereon and connecting members inserted in the end portions; and

Figure 5 is a reduced size and elevational view taken along line V—V of Figure 4.

As shown on the drawings:

As shown in Figure 1, a substantially flat metal blank 10 has a downwardly offset central section 11 of greater width than end sections 12 thereof. Inclined flanges 11a connect the central portion 11 with the ends 12. Tabs or kerfs 13 are pressed angularly downwardly from the metal of the blank, two in each end section 12, the tabs lying substantially along a single longitudinal line. The longitudinal side edges of the end sections are recessed or indented along their length as at 14 and have inwardly rounded outer ends 14a and outwardly rounded inner ends 14b.

In Figures 2, 3, 4 and 5 is shown a turnbuckle barrel 15 which is formed by rolling the blank 10 of Figure 1 into tubular shape. The longitudinal edges of the central section 11 are abutted firmly together as by welding 16. The central section 11 of the blank 10 forms a diametrically enlarged central portion 17 of the barrel 15. End portions 18 are formed by the end sections 12 and have slots 19 therein formed by the recessed edges 14. Each slot has an outwardly flared rounded entrance mouth 19a formed by the ends 14a and a rounded bottom 19b formed by the ends 14b.

The ends 18 and central portion are joined by the sloping shoulders 17a formed from the flanges 11a. Retaining lugs 20, diametrically opposite to the slots 19, are formed by the tabs 13 of the blank 10.

As best seen in Figures 2 and 3, the end portions 18 have internal threads 21, the threads in one end portion being right hand and those in the other end portion being left hand. The threads 21 are preferably formed after the weld 16.

It should be noted that the inside diameter of the central portion 17 is greater than the major diameter of the internal threads 21. Hence, the inner surface of the central portion 17 remains smooth and unnotched and consequently is free from any points of unnecessary stress concentration.

Referring to Figure 4, clamping rings 22 are disposed over the end portions 18 of the barrel 15 and are prevented from axial movement thereon by the lugs 20. The rings 22 have outwardly clamping ears 23 at either side of their longitudinal slots 24. Bolts 25 are inserted through holes in the ears and extend across the slots 24. Nuts 26 are threadededly inserted onto the ends of bolts 25 and have lock washers 27 thereunder.

Connecting members 28 and 29 having externally threaded portions 30 and 31 respectively are threadededly

inserted into the end portions 18 of the barrel 15 to engage with the internal threads 21 formed therein.

It is apparent from the structure described that rotation of the barrel 15 in one direction will serve to further insert both of the connecting members 28 and 29 into the barrel thereby tightening the connection. Conversely, rotation of the barrel 15 in the opposite direction will serve to loosen the connection. When the desired relationship between the connecting members 28 and 29 has been achieved, the nuts 26 are tightened down on the bolts 25 thereby tightening the clamping rings 22 about the end portions 18. Thus, the walls of the end portions 18 will be pressed firmly against the threaded sections 30 and 31, thereby effecting a tight, non-rotating connection between the connecting members 28 and 29.

From the above description it will be understood that the present invention provides an improved turnbuckle having a non-threaded, diametrically enlarged central portion which serves to increase the strength of the barrel without materially changing the conventional method of forming such turnbuckles and without increasing the gauge of the metal used in forming the barrel. It can be readily seen that the turnbuckle barrel is expeditiously (but not necessarily) manufactured by rolling a previously formed substantially flat blank into the proper tubular shape. When formed in such a tubular shape, internal threads are easily cut in the ends of the barrel, and since the enlarged central portion has a larger inside diameter than the major diameter of the threads, each of the threaded portions may be of minimum length for proper engagement while still allowing for proper adjustment within the unthreaded central portion. As a further result of the increased diameter central portion, threading of the end portion may be easily accomplished without precise control over the depth of 35

insertion of a threading tool, resulting in further increase in ease of manufacture. Easily formed lugs serve to retain clamping rings on each end of the barrel so that the rings will be retained in proper axial position on the ends of the barrel and will not slip off the ends when loosened to allow insertion of the connecting members.

It will be understood that modifications and variations may be effected without departing from the scope of the novel concepts of the present invention.

10 I claim as my invention:

In a tubular clamping structure, a tube comprising a single curled sheet, of substantially uniform thickness having its central portion of wider extent than the end portions thereof and depressed radially and cylindrically outwardly with longitudinally juxtaposed edges extending and offset circumferentially beyond the opposite and remaining end portions of the tube and joined together leaving gaps in the end portions longitudinally aligned with said joined edges, said depressed central portion at each of its ends having an annular reinforcing shoulder merging into the adjoining tube end portion adjacent the inner end of the associated gap in the end portion as well as adjacent an end of the joined edges.
